GLUING FRAME

Robert Greevy, Los Angeles, Calif., assignor to
 Summerbell Roof Structures, Los Angeles,
 Calif., a corporation of California

Application March 9, 1942, Serial No. 433,933

12 Claims. (Cl. 144—279)

This invention relates to a gluing frame of the character employed for gluing up the timbers to form a laminated wooden structure. It is particularly adapted to the gluing up of the laminations of curved wooden structures such as for example, arches and the curved top chords of roof trusses, although it may be used for gluing up the laminations of straight wooden structures.

An object of the invention is to provide a gluing frame having a series of adjustable uprights against which the timbers that form the laminations may be positioned and to provide means for temporarily holding the timbers in applied position prior to tightening the timbers in firm engagement with each other against the uprights.

Another object of the invention is to provide a gluing frame wherein the various parts are readily adjustable enabling structures to be glued up which have varying radii of curvature and which may be of various cross sections, such as for example, ordinary laminated arches or curved chords, ledger chords, and the like.

A further object of the invention is to provide an improved gluing frame which is so designed that a plurality of separate laminated structures may be assembled thereon and glued up together independently of each other so that when the frame is completely loaded a large number of laminated structures may be held in compression while the glue thereon is drying or hardening. In this manner a plurality of structures can be produced simultaneously upon a single loading of the glue frame.

With the foregoing and other objects in view, which will be made manifest in the following detailed description and specifically pointed out in the appended claims, reference is had to the accompanying drawings for an illustrative embodiment of the invention, wherein:

Figure 1 is a top plan view of an end portion of the gluing frame embodying the present invention, this portion being typical of the entire length of the gluing frame and parts of the uprights being illustrated in horizontal section;

Fig. 2 is a view in side elevation parts being illustrated in vertical section illustrating one of the uprights of the gluing frame and the manner in which the gluing frame is loaded;

Fig. 3 is a partial view in front elevation of the lower portion of the upright illustrated in Fig. 2;

Fig. 4 is a view in vertical section through a portion of one of the uprights illustrating the laminations forming one of the wooden structures in the process of being tightened up;

Fig. 5 is a view similar to Fig. 4, illustrating the laminations as having been completely tightened against each other;

Fig. 6 is a horizontal section taken substantially upon the line 6—6 upon Fig. 5; and

Fig. 7 is a section perspective view of a portion of one of the uprights.

Referring to the accompanying drawings wherein similar reference characters designate similar parts throughout, inasmuch as the improved gluing frame has been primarily designed for the gluing up of curved wooden structures, such as arches, the top chords of trusses, and the like, it will be described primarily with reference thereto.

To this end, the improved gluing frame comprises outer and inner curved sills 10 and 11 which extend the entire length of the gluing frame. These sills may be bolted to the floor such as by bolts 12 and 13. They have curvatures that roughly correspond to the majority of the curved laminated structures that are to be glued up. On these sills there is a series of base members 14, each of which is equipped with an upright 15 held in upright position by diagonal braces 16. The base members 14 have radial outer slots 17 and radial inner slots 18. Similarly the sills 10 and 11 have longitudinally extending slots 19 and 20. Bolts 21 extend through the slots 17 and 19 and similar bolts 22 extend through the slots 18 and 20. Thus by loosening the bolts 21 and 22 the individual units that provide the upright members 15 can be adjusted with respect to the sills so that the outer faces of the uprights may be positioned on any desired curvature which may or may not conform to the curvature of the sills. By means of this adjustment a single gluing frame can be varied or adjusted to glue up laminated wooden structures having various radii of curvature.

The upright members 15 are preferably made of three laminations each such laminations being indicated at 23, 24, and 25. The center lamination has its sides grooved as at 26 and 27, see Fig. 7, to accommodate the legs 28 and 29 of stirrups 30. The grooves 26 and 27 are shaped as illustrated in Fig. 7 so that the stirrups may either assume upwardly and forwardly inclined positions with respect to the uprights 15 as illustrated by the two uppermost stirrups shown in Fig. 2, or they may assume and be limited to horizontal positions as shown by the four lowermost stirrups illustrated in Fig. 2. The legs of the stirrups 28 and 29 are slidable through the grooves 26 and 27 which form slots in the uprights and

have a series of apertures 31 formed therein through which a bar 32 may be positioned. Thus, the stirrup may be adjusted forwardly or rearwardly with respect to the upright member 15 and a bar inserted in the proper aperture 31 to hold or lock the stirrup in the desired position. The rear face of the upright is preferably equipped with a steel plate 33 against which the bar 32 bears. The forward end of each stirrup 30 is widened to accommodate the tops and bottoms of bridging blocks 34. Spacers 35 tend to resist collapse of the widened forward portions of the stirrups. The bridging blocks 34 are preferably shouldered as at 36 to accommodate the foremost portions of the stirrups. The reduced portions of the bridging blocks above and below the shoulder 36 enter the stirrups vertically adjacent thereto. Each bridging block has two apertures extending horizontally therethrough one such aperture being indicated at 34a and the other at 34b. Jackscrews 37 are optionally receivable in either the apertures 34a or 34b. These jackscrews are screwed through nuts 38 that are welded onto U-shaped brackets that embrace the rear edges of the bridging blocks. Each jackscrew has a swivelled foot 39 that is adapted to engage and tighten up the laminations of the wooden structure that is to be produced.

As will be noted from an inspection of Fig. 6, each bar 32 is of such a length that it extends laterally beyond the side of the adjacent upright 15. This projecting portion is adapted to receive and pivotally support a series of dogs 40. The dogs that compose each set mounted on a bar 32 are of various lengths and have hooked outer ends indicated at 41 adapted to engage the outer sides of the individual laminations. The foremost faces of the dogs are cam-shaped as indicated at 42 so that as the laminations are tightened towards the uprights 15 by the jackscrew 37 the dogs may be consecutively cammed or squeezed out from between the laminations as they are brought into surface to surface contact.

The operation and advantages of the improved gluing frame are as follows: Assuming that it is desired to produce a laminated wooden structure 50 feet in length and having a radius of curvature of 50 feet, the various timbers T that are to form the laminations of such a structure are first assembled or made up. These timbers may be made up of small segments secured together by glued scarf joints or the equivalent. Each timber is of the required length and may have glue applied to its opposed faces. The innermost timber is first positioned against the uprights adjacent the center of the glue frame on top of the lowermost stirrup. As the timber will normally tend to remain straight its ends will tend to remain spaced from its uprights 15 that are arranged toward the ends of the glue frame as illustrated in Fig. 1.

In order to maintain the first timber in applied position the shortest dog 40 is swung about bar 32 as a center and has its hooked forward end positioned against the outer face of the lamination as illustrated in Fig. 4. Succeeding laminations may then be applied and temporarily held in position by being engaged by their respective dogs 40. When the entire number of laminations that are to form the wooden structure have been thus assembled the bridging blocks 34 are then positioned in the lowermost stirrups and the stirrups next above are swung to horizontal positions so as to engage the upper ends of the bridging blocks. The jackscrews 37 then have

wrenches applied to their squared outer ends and are tightened to force the caps or plates 39 toward the upright members 15. In the course of tightening, the outermost lamination will be tightened first into engagement with the next innermost lamination as illustrated in Fig. 4, and as these two laminations come into surface to surface contact the dogs that engage between these laminations are squeezed or are cammed out as illustrated in Fig. 4. The tightening of the jackscrew is continued until all laminations are brought into surface to surface contact and all dogs are squeezed out as indicated in Fig. 5.

The laminations are then left in the position shown in Fig. 5 until the glue dries or sets after which the jackscrew can be loosened, the stirrups swung upwardly into inclined positions, such as are illustrated at the top of Fig. 2, and the bridging blocks removed to permit removal of the completed glued up structure from the frame.

The assembly of the timbers making one laminated structure on the gluing frame does not tie up the entire frame while its glue is drying or setting. The timbers of succeeding arches or chords can be similarly assembled between the stirrups thereabove and independently tightened toward the uprights 15 as illustrated in Fig. 2. Usually if the arch or chord is relatively narrow and has straight sides two arches or chords may be simultaneously assembled together and tightened up between two adjacent stirrups. These arches or chords are separated from one another by a spacer or batten strip 43. If, however, the arch or chord has a ledger such as is indicated at 44, usually only one laminated structure is tightened between two adjacent stirrups.

It will, of course, be appreciated that the sets of dogs 40 will not be uniform for all of the upright members 15. Thus, those dogs that are near the center of the gluing frame will be somewhat shorter than the sets of dogs near the ends of the frame. In other words, in Fig. 1, the set of dogs applied to the endmost upright 15 will be slightly longer than the set of dogs applied to inner upright members and these will consecutively decrease from the ends of the frame toward the center. With this arrangement it is relatively easy for the timbers that are to make up the completed structure to be assembled together on the gluing frame and temporarily held against the uprights prior to the tightening up of the laminations by the jackscrews. During the tightening operation the dogs are removed or are squeezed out automatically.

If it is desired to glue up a laminated wooden structure having a different radius of curvature the bolts 21 and 22 are loosened and the various units that provide the upright members are adjusted so that the upright members will be arranged on the desired curvature. During such sliding adjustment there is danger or tendency for the units to tilt on the sills 10 and 11 which might cause the bolts 21 and 22 to split the base members 14, particularly adjacent their forward ends. To guard against this it is advisable to glue in transverse dowels 45 through the forward ends of the base members to resist such splitting.

From the above-described construction it will be appreciated that the improved gluing frame is highly advantageous in that it is readily adjustable to manufacture laminated wooden structures having various radii of curvature that a plurality of such structures can be tightened up and held in curved position simultaneously while the glue thereon is drying or setting, and that by

the use of the dogs it is very easy to assemble the timbers forming the laminations together against the upright members and hold them temporarily prior to the complete tightening up. If the glue frame is to be used for gluing up straight laminated structures it is sometimes possible to adjust the units on the sills 10 and 11 so that all of the uprights 15 are arranged on a straight line. This is particularly true if the laminated structure is short. If not, it may be necessary to 10 mount the upright providing units on straight rather than curved sills.

Various changes may be made in the details of construction without departing from the spirit or scope of the invention as defined by the appended claims.

I claim:

1. A gluing frame comprising a plurality of uprights against which timbers to be glued can be positioned, means for tightening the timbers against the uprights, and dogs mounted on the uprights engageable with the outer sides of the timbers for temporarily holding the timbers against the uprights prior to the tightening of said tightening means, said dogs having outer cam surfaces enabling them to be squeezed or cammed out from between the timbers as they are tightened up by the tightening means.

2. A gluing frame comprising a plurality of spaced uprights against which timbers to be glued may be tightened, stirrups adjustably mounted on the uprights, bridging blocks adapted to be positioned in adjacent stirrups, said bridging blocks having jackscrews arranged to tighten the timbers against the uprights, there being slots formed in the uprights adapted to receive the legs of the stirrups, said slots being so formed that the stirrups may assume horizontal positions extending forwardly from the uprights or upwardly and forwardly inclined positions with respect thereto, cross bars receivable in any of a plurality of holes in the stirrups, and dogs pivoted on the cross bars engageable with the outer sides of the individual timbers to temporarily hold the timbers against the uprights prior to the tightening of the jackscrews.

3. A gluing frame comprising front and rear sills, units providing uprights adjustably mounted on said sills, a plurality of stirrups adjustably mounted on each upright, bridging blocks receivable between the forward ends of adjacent stirrups, jackscrews carried by the bridging blocks, bars receivable in holes in the stirrups and sets of dogs pivotally mounted upon said bars, said dogs being arranged to engage and temporarily hold timbers against uprights prior to the tightening up of the jackscrews.

4. A gluing frame comprising front and rear sills, units providing uprights adjustably mounted on said sills, a plurality of stirrups adjustably mounted on each upright, bridging blocks receivable between the forward ends of adjacent stirrups, jackscrews carried by the bridging blocks, bars receivable in holes in the stirrups and sets of dogs pivotally mounted upon said bars, said dogs being arranged to engage and temporarily hold timbers against uprights prior to the tightening up of the jackscrews, said dogs having cammed outer faces whereby they may be automatically squeezed out from between the timbers as the timbers are tightened against each other.

5. A gluing frame comprising a plurality of spaced uprights against which timbers to be glued may be tightened, a plurality of stirrups pivotally mounted on the uprights in vertical

alignment, bridging blocks adapted to be positioned between vertically adjacent stirrups, each bridging block being adapted to bridge the space between the adjacent stirrups and to only partially extend therethrough whereby adjacent ends of adjacent bridging blocks may be received in and held by the same stirrup, and means on the bridging blocks for tightening the timbers toward the uprights.

6. A gluing frame comprising a plurality of spaced uprights against which timbers to be glued may be tightened, a plurality of stirrups pivotally mounted on the uprights in vertical alignment, bridging blocks adapted to be positioned between vertically adjacent stirrups, each bridging block being adapted to bridge the space between the adjacent stirrups and to only partially extend therethrough whereby adjacent ends of adjacent bridging blocks may be received in and held by the same stirrup, means on the bridging blocks for tightening the timbers toward the uprights, and means for supporting the lowermost stirrup.

7. A gluing frame comprising a plurality of spaced uprights against which timbers to be glued may be tightened, a plurality of bridging blocks adapted to be positioned forwardly of the uprights, tightening means on the bridging blocks for tightening timbers to be glued against the uprights, and a stirrup mounted on the uprights and extending forwardly therefrom for each pair of vertically adjacent bridging blocks and within which the adjacent ends of adjacent bridging blocks is receivable.

8. A gluing frame comprising a plurality of spaced uprights against which timbers to be glued may be tightened, a plurality of bridging blocks adapted to be positioned forwardly of the uprights, tightening means on the bridging blocks for tightening timbers to be glued against the uprights, and a stirrup mounted on the uprights and extending forwardly therefrom for each pair of vertically adjacent bridging blocks and within which the adjacent ends of adjacent bridging blocks is receivable, each stirrup being pivotally and adjustably mounted on the uprights.

9. A gluing frame for gluing up a curved laminated structure made up of individual timbers comprising a plurality of spaced uprights arranged in accordance with the curvature of the structure and against which the timbers to be glued may be tightened, means on the uprights extending forwardly therefrom for tightening the timbers against the uprights, and a plurality of dogs of consecutively increasing length pivotally mounted adjacent the uprights and extending forwardly therefrom engageable with the outer sides of the individual timbers for temporarily holding the individual timbers pressed toward the uprights prior to tightening the timbers thereagainst by the tightening means.

10. A gluing frame for gluing up a curved laminated structure made up of individual timbers comprising a plurality of spaced uprights arranged in accordance with the curvature of the structure and against which the timbers to be glued may be tightened, means on the uprights extending forwardly therefrom for tightening the timbers against the uprights, and a plurality of dogs of consecutively increasing length pivotally mounted adjacent the uprights and extending forwardly therefrom engageable with the outer sides of the individual timbers for temporarily holding the individual timbers pressed toward the uprights prior to tightening the timbers

thereagainst by the tightening means, said dogs having cammed outer faces arranged to automatically shift the dogs from between the timbers as the timbers are tightened into engagement with each other.

11. A gluing frame for gluing up a curved laminated structure made up of individual timbers comprising a plurality of spaced uprights arranged in accordance with the curvature of the structure against which the timbers to be glued may be tightened, a plurality of stirrups adjustably mounted on each upright and extending forwardly therefrom, bridging blocks connecting the forward ends of the stirrups, tightening means on the bridging blocks for tightening the timbers against the forward faces of the uprights, and a plurality of dogs of consecutively increasing length pivotally mounted on the stirrups for engaging the outer sides of the individual timbers and holding them pressed toward the uprights prior to tightening the timbers thereagainst by the tightening means.

12. A gluing frame for gluing up a curved laminated structure made up of individual timbers comprising a plurality of spaced uprights arranged in accordance with the curvature of the structure against which the timbers to be glued may be tightened, a plurality of stirrups adjustably mounted on each upright and extending forwardly therefrom, bridging blocks connecting the forward ends of the stirrups, tightening means on the bridging blocks for tightening the timbers against the forward faces of the uprights, and a plurality of dogs of consecutively increasing length pivotally mounted on the stirrups for engaging the outer sides of the individual timbers and holding them pressed toward the uprights prior to tightening the timbers thereagainst by the tightening means, said dogs having cammed outer faces arranged to automatically shift the dogs from between the timbers as the timbers are tightened into engagement with each other.

ROBERT GREEVY.
